UNITED STATES PATENT OFFICE.

CHARLES G. SMITH, OF MEDFORD, MASSACHUSETTS, ASSIGNOR, BY MESNE ASSIGNMENTS, TO S-TUBE CORPORATION, OF DOVER, DELAWARE, A CORPORATION OF DELAWARE.

ELECTRICAL APPARATUS.

Application filed August 30, 1920. Serial No. 406,886.

To all whom it may concern:

Be it known that I, CHARLES G. SMITH, a citizen of the United States, residing at Medford, in the county of Middlesex and State of Massachusetts, have invented certain new and useful Improvements in Electrical Apparatus; and I do hereby declare the following to be a full, clear, and exact description of the invention, such as will enable others skilled in the art to which it appertains to make and use the same.

The present invention relates to electrical apparatus and more particularly to apparatus of this character involving electrical circuits which include a gaseous medium as part of the circuit.

I have discovered that it is possible by the proper design and location of electrodes immersed in a gas to insulate and restrict conduction through the gas even though the space separating the electrodes is subjected to a high potential gradient. I accomplish this result by making the space between juxtaposed surfaces of the electrodes sufficiently short to prevent initiation of substantial conduction directly across said space by potentials high enough to initiate conduction across longer gaps, and at the same time preventing substantial conduction between the non-opposed or back areas of the electrodes around the boundary of said space. In the present instance, the surfaces of the cooperating electrodes are spaced apart a distance which is comparable to and of the order of magnitude of the mean free paths of electrons in the gas in which the electrodes are immersed. This mean free path may be defined as the average distance which an electron travels at ionizing velocity before ionizing impact with a gas molecule (or atom). The value of this mean free path in any given gas is affected by the pressure under which the gas is placed. By a particular design and location of cooperating electrodes, in the present instance two cylindrical tubes of different diameters concentrically located, I can insure that all paths available for discharge through the gas are short and of the order of magnitude of the mean free paths of electrons in the gas and by proper design of the insulating and supporting dielectric I can insure that all paths through the dielectric are sufficiently long to prevent breakdown under the applied voltage.

With such a construction, it is possible to

prevent conduction through the gas between the juxtaposed surfaces of the electrodes with relatively high potential differences and gas pressures corresponding to one one-hundredth of a millimeter of mercury, or 60 more.

It will be seen that this invention involves principles not heretofore embodied in the usual type of low pressure gaseous discharge apparatus. With my invention it is possible to impress extremely high potential gradients in the gas without causing conduction between juxtaposed surfaces.

A simple and efficient application of my invention is embodied in a vacuum condenser 70 having two concentric metal tubes of cylindrical form positioned and located by suitably designed insulating supports, and all enclosed within a gas-filled receptacle of insulating material. The arrangement of the 75 tubes which are at different potentials is such that the distance through the gas between all juxtaposed surfaces at different potential gradient is sufficiently short to prevent gaseous conduction. In this particular embodiment all available paths for the discharge of electrons through the gaseous medium are of the order of magnitude of the mean free path of the electrons, and all paths through the insulating material are sufficiently long 80 to prevent breakdown and consequent discharge therethrough.

The accompanying drawing illustrates in section a vacuum condenser embodying the 90 invention.

The illustrated embodiment of the invention discloses a vacuum condenser embodying a plurality of electrodes or plates at different potentials, all immersed in a gas, the 95 plates being designed and located in such a manner that the only paths available for short circuit through the gaseous medium are too short to permit the initiation of electron discharge. According to this design, the condenser will not break down by discharge under a potential difference of 10,000 100 volts, even when the gas in which the electrodes or plates are immersed is at a pressure as great as $\frac{1}{10}$ of a millimeter.

Upon referring to the accompanying 105 drawing, it will be observed that the condenser comprises two concentric cylinders 10 and 12 of conducting material, enclosed within a gas-filled receptacle 14 of glass or other insulating material. The tubes 10 and 110

12 are retained in concentric relation by insulating supports 16 and 18. Each of these supports, as shown, is provided with an enlarged base portion 20, fitting within and holding the outer tube 12, and a smaller head portion 22, fitting within the inner tube 10. In addition the insulating supports may be provided with a reduced neck 24, which provides an insulating gap between 10 the end of the inner tube or cylinder and the insulating support. As will be observed, with this construction all direct paths for electron discharge between the surfaces of the cylinders at different potentials are 15 short, and in addition all paths available for discharge between these surfaces through the insulating support are long. As will be observed from an inspection of the drawing, the lower insulating support 18 may be 20 conveniently provided with a base 26 fitting closely within the receptacle 14 and held therein in any suitable manner. With this construction, the cylinders are held in the proper positions within the receptacle. The 25 circuit leads may be conveniently disposed, as shown, the connection with the outer tube 12 being indicated at 28 as attached to the upper edge of the tube, and the connection for the inner tube being indicated at 30 as 30 attached to the inner surface of the tube between the insulating supports, passing outwardly through the insulating supports and the opposite end of the tube. The condenser may obviously be included in any 35 desired form of circuit.

The theory underlying the operation of this device may be stated briefly as follows: The conductivity of a gas at any instant may be said to depend upon the number 40 of ions present. This number is usually small but is rapidly increased by ionization by collision upon impressing a sufficient potential gradient. In addition, the distribution is such as to make the conductivity 45 of the gas under pressure, or with only a partial vacuum, relatively good. The presence of these ions which render the gas conductive is due to the collision of electrons or ions with atoms or molecules, resulting in the 50 production of more ions, which in turn collide with other atoms, and continue to produce still more ions. If the electrons given off from one electrode have normally only a short distance to travel before arriving at the 55 opposite electrode, their chances for collision are small, providing that the distance of separation of the electrodes is sufficiently short. It has been found possible to so proportion the distance which the electrons will travel 60 that there are not a sufficient number of collisions between electrons and atoms to produce a sufficient number of positive ions to bombard the cathode and liberate electrons for the initiation of substantial gaseous conduction. Although in practice there are un-

doubtedly some stray positive ions always present, it is a fact that with the distance properly designed, as hereinbefore indicated, their number is insufficient to give rise to further positive ions and cause substantial 70 gaseous conduction to take place.

It is believed that this theory is substantially correct as stated, but independently of the correctness of the theory, it is a fact that by designing and locating the electrodes in 75 such a manner that the direct paths for electron discharge through the gaseous medium between juxtaposed surfaces of the electrodes are relatively short and of the order of magnitude of the mean free path of the electrons 80 it is possible to insulate with a relatively poor vacuum the same differences of potential that previously required a substantially perfect vacuum.

It is believed that for best results the length 85 of said direct paths through the gas between juxtaposed surfaces of the electrodes at different potentials should be shorter than the mean free path of the electrons; but owing to the difficulty of exactly estimating the 90 length of the mean free path, it is only known absolutely that the length of the available paths should be comparable to the mean free path of the electrons, and it may be possible to construct an insulating gap 95 according to my new discovery even though the length of the available paths is as great, or greater, than the length of the mean free path and still be within the scope of the invention so long as these paths are sufficiently 100 short to prevent substantial ionization.

From the foregoing it will be evident that each of the insulation blocks 16 and 18 constitutes an obstruction at one boundary of the space between the juxtaposed surfaces 105 of the electrodes which prevents substantial conduction around the boundary between surfaces of the electrodes outside said boundary. In the illustrated embodiment said boundary may be considered to be an imaginary ring extending from one end of electrode 10 to the electrode 12 in the radial plane of the end of electrode 10. This obstruction may be spaced from the electrode as at 24 or when formed of insulation it 110 may contact with the electrode as at 20. This obstruction is shaped and arranged to afford no path between the two electrodes along its surfaces as short as the shortest distance between the juxtaposed surfaces of 115 the electrodes and in the illustration the shortest path between the electrodes along its surface is more than ten times the shortest distance between the two electrodes.

An important characteristic of the present invention consists in that one electrode is hollow and the other electrode has a surface presented to the interior surface of the hollow electrode, the areas of the two surfaces being unequal.

By making the surfaces of the two electrodes unequal in area the resistance of the air gap is greater in one direction than in the other direction. This feature is useful in many applications of the invention. For example, the condenser illustrated in the drawing is particularly applicable in pulsating direct current circuits where a condenser has a greater tendency to break down in one direction than in the other direction.

It should be understood that the present invention is not limited in its application to the particular embodiment here shown, but is susceptible of embodiment in a wide variety of electrical circuits embodying gaseous mediums.

Having thus described the invention, what is claimed is:

1. Electrical apparatus comprising an electrode having an extended surface area, and a second electrode having an area of lesser extent presented to said area across an intervening space, the space between juxtaposed surfaces of the electrodes being sufficiently short and the gas pressure being sufficiently low to prevent initiation of substantial conduction directly across said space by potentials high enough to initiate conduction across longer gaps, and means for preventing substantial conduction between other areas of said electrodes around the boundary of said space.

2. Electrical apparatus comprising an electrode having an extended surface area, and a second electrode of different size presented to said area across an intervening space, the space between juxtaposed surfaces of the electrodes being sufficiently short and the gas pressure being sufficiently low to prevent initiation of substantial conduction directly across said space by potentials high enough to initiate conduction across longer gaps.

3. Electrical apparatus comprising a hollow electrode and a second electrode presented to the interior surface of the hollow electrode across an intervening space, the space between juxtaposed surfaces of the electrodes being sufficiently short and the gas pressure being sufficiently low to prevent initiation of substantial conduction directly across said space by potentials high enough to initiate conduction across longer gaps, and means for preventing substantial conduction between the exterior surface of said hollow electrode and the second electrode.

4. Electrical apparatus comprising an electrode having an extended surface area, and a second electrode presented to said area across an intervening space, the space between juxtaposed surfaces of the electrodes being sufficiently short and the gas pressure being sufficiently low to prevent initiation of substantial conduction directly across said space by potentials high enough to initiate

conduction across longer gaps, and an obstruction adjacent boundaries of said surfaces, the obstruction extending sufficiently close to each electrode to prevent substantial conduction around the boundary of said space and the obstruction being shaped and arranged to afford no path between the two electrodes along its surface as short as the shortest distance between said juxtaposed surfaces across said space.

5. Electrical apparatus comprising a hollow electrode and a second electrode presented to the interior surface of the hollow electrode across an intervening space, the space between juxtaposed surfaces of the electrodes being sufficiently short and the gas pressure being sufficiently low to prevent initiation of substantial conduction directly across said space by potentials high enough to initiate conduction across longer gaps, and an obstruction adjacent boundaries of said surfaces, the obstruction extending sufficiently close to each electrode to prevent substantial conduction between the electrodes around the boundary of said space.

6. Electrical apparatus comprising two non-filamentary electrodes of different shapes with a rarified gas space therebetween, one electrode having an extended surface area presented to the other electrode, the space between juxtaposed surfaces of the electrodes being sufficiently short to prevent initiation of substantial conduction directly across said space by potentials high enough to initiate conduction across longer gaps.

7. Electrical apparatus comprising two non-filamentary electrodes formed of solid material with a rarified gas space therebetween, one electrode being hollow and the other electrode being presented to the interior surface thereof, the space between juxtaposed surfaces of the electrodes being sufficiently short to prevent initiation of substantial conduction directly across said space by potentials high enough to initiate conduction across longer gaps, and means for preventing substantial conduction between the exterior surface of said hollow electrode and the second electrode.

8. Electrical apparatus comprising two non-filamentary electrodes formed of solid material with a gas space therebetween, one electrode having an extended surface area presented to the other electrode, the space between juxtaposed surfaces of the electrodes being sufficiently short and the gas pressure being sufficiently low to prevent initiation of substantial conduction directly across said space by potentials high enough to initiate conduction across longer gaps, and insulation adjacent boundaries of said surfaces, the insulation extending sufficiently close to each electrode to prevent substantial conduction between the electrodes.

around the boundary of said space and the shortest distance between the electrodes along the surface of the insulation being longer than the shortest distance between 5 said juxtaposed surfaces across said space.

9. Electrical apparatus comprising two non-filamentary electrodes with a gas space therebetween, one electrode being hollow and the other electrode being presented to the 10 interior surface thereof, the space between juxtaposed surfaces of the electrodes being sufficiently short and the gas pressure being sufficiently low to prevent initiation of substantial conduction directly across said 15 space by potentials high enough to initiate conduction across longer gaps, and insulation adjacent boundaries of said surfaces, the insulation extending sufficiently close to each electrode to prevent substantial conduction 20 between the electrodes around the boundary of said space.

10. Electrical apparatus comprising a hollow electrode having an open end and a second electrode presented to the interior 25 surface of the hollow electrode adjacent said end, with a rarified gas space therebetween, the space between juxtaposed surfaces of the electrodes being sufficiently short to prevent initiation of substantial gaseous 30 conduction between said surfaces by potentials high enough to initiate conduction across longer gaps, and insulating material substantially closing said open end of the hollow electrode.

35 11. Electrical apparatus comprising electrodes having juxtaposed surfaces with a gas space therebetween, and insulation material extending sufficiently close to boundaries of said surfaces to prevent substantial conduction 40 between the electrodes around the boundary of said space, the shortest distance between electrodes along the surface of the insulation being sufficiently long to prevent substantial conduction between electrodes 45 along the surface of the insulation, and the space between juxtaposed surfaces of the electrodes being sufficiently short and the gas pressure being sufficiently low to prevent initiation of substantial conduction directly 50 across said space by a potential at which conduction is resisted by said insulation.

55 12. Electrical apparatus comprising electrodes having opposed surfaces of different areas with a gas space therebetween, said space being comparable in length to the mean free path of electrons in the gas, and insulation disposed at boundaries of said surfaces, said insulation extending sufficiently close to each electrode to prevent substantial conduction 60 between the electrodes around the boundary of said space.

65 13. Electrical apparatus comprising electrodes having opposite surfaces with a gas space therebetween, said space being comparable in length to the mean free path of

electrons in the gas, one electrode surrounding a part of the other electrode, and insulation disposed at boundaries of said surfaces, said insulation extending sufficiently close to each electrode to prevent substantial conduction between the electrodes 70 around the boundary of said space.

14. Electrical apparatus comprising electrodes having opposite surfaces with a gas space therebetween, one dimension of said 75 space being comparable to the mean free path of electrons in the gas, and insulation confining said space in another dimension, said insulation extending substantially from one electrode to the other and the 80 shortest distance between the electrodes along the confining surface of the insulation being longer than said dimension.

15. Electrical apparatus comprising electrodes having opposite surfaces with a rarified gas space therebetween, one electrode surrounding a part of the other electrode, and insulating material disposed at boundaries of said surfaces, said insulating material extending sufficiently close to each electrode to prevent substantial conduction between the electrodes around the boundary of said space and the shortest distance between electrodes along the surface of the insulation being greater than the shortest distance 90 between electrodes across said space. 95

16. Electrical apparatus comprising electrodes having therebetween a rarified gas gap of such length as to restrict gaseous conduction along the shortest path between the electrodes, and means for obstructing gaseous discharge along long paths including insulation extending along one electrode in close juxtaposition thereto. 100

17. Electrical apparatus comprising two concentric electrodes of solid conducting material, a gas-filled receptacle enclosing the electrodes, insulation for retaining the electrodes in concentric relation, the space between juxtaposed surfaces of the electrodes being sufficiently short and the gas pressure being sufficiently low to prevent initiation of substantial gaseous conduction directly across the space by potentials high enough to initiate conduction across longer 110 gaps. 115

18. An electrical apparatus comprising two concentric tubes of conducting material, a gas-filled receptacle enclosing the tubes, insulating supports for retaining the tubes in concentric relation, the surfaces of the tubes at different potentials being spaced apart a distance which is short and of the order of magnitude of the mean free path of the electrons in the gas. 120 125

19. An electrical apparatus comprising a gas-filled receptacle, concentric tubes of conducting material fitted within the receptacle, means for retaining the tubes in concentric relation, and separated by a dis- 130

tance less than the normal mean free path of the electrons through the gas to normally prevent gaseous conduction across the gap between the tubes.

- 5 20. Electrical apparatus comprising electrodes having opposite surfaces with a gas space therebetween, one dimension of said space being comparable to the mean free path of electrons in the gas, and insulating material confining said space in another dimension, said insulating material contacting with one electrode at the boundary of its said surface and having its confining surface spaced from the other surface a distance comparable to said mean free path.
- 10 21. Electrical insulating apparatus comprising a hollow electrode and a second electrode disposed within said hollow electrode and presented to the interior surface of the
- 15 20. hollow electrode across an intervening

space, the space between juxtaposed surfaces of the electrodes being sufficiently short and the gas pressure being sufficiently low to prevent initiation of substantial conduction directly across said space by potentials high enough to initiate conduction across longer gaps, and means for preventing substantial conduction between the exterior surface of said hollow electrode and the second electrode. 25

22. A condenser comprising a gas-filled receptacle, concentric tubes of conducting material fitted within the receptacle, means for retaining the tubes in concentric relation, and separated by a distance less than 30 the normal mean free path of the electrons through the gas to normally prevent gaseous conduction across the gap between the tubes in both directions. 35

CHARLES G. SMITH.
